(57) **CLAIM**

The ornamental design for a bottle, as shown.

DESCRIPTION

FIG. 1 is front, side, and top perspective view of a bottle that has the design.

FIG. 2 is front, side, and bottom perspective view of the bottle.

FIG. 3 is a front elevational view of the bottle.

FIG. 4 is a back elevational view of the bottle.

FIG. 5 is a right-side elevational view of the bottle.

FIG. 6 is a left-side elevational view of the bottle; and,

FIG. 7 is a top plan view of the bottle.

The dots, the Pepsi logo, and the curved lines beneath the Pepsi logo are all raised/convex.

The Pepsi logo that forms part of the claimed design is a variant of a registered trademark of Pepsico Incorporated.
